(57) **CLAIM**

The ornamental design for control elements for an electrical device, as shown and described.

DESCRIPTION

FIG. 1 is a plan view of the control elements for an electrical device, showing our new design;

FIG. 2 is a right-side elevational view thereof, it being understood that the left side is a mirror image thereof;

FIG. 3 is a bottom view thereof; and,

FIG. 4 is a right, top perspective view thereof.

The broken lines define the bounds of the claimed design.
